UNITED STATES PATENT OFFICE.

JACOB GREENWALD, OF PHILADELPHIA, PENNSYLVANIA, ASSIGNOR TO HIMSELF, THEODORE GREENWALD, AND MAX GREENWALD, TRADING AS GREENWALD BROS., OF PHILADELPHIA, PENNSYLVANIA.

LADY'S SKIRT.

No. 855,885.

Specification of Letters Patent.

Patented June 4, 1907.

Application filed January 25, 1907. Serial No. 354,091.

To all whom it may concern:

Be it known that I, JACOB GREENWALD, residing at No. 1251 North Thirteenth street, in the city of Philadelphia, in the county of Philadelphia and State of Pennsylvania, have invented certain new and useful Improvements in Ladies' Skirts, whereof the following is a specification, reference being had to the accompanying drawings.

10 In said drawings, Figure I, represents a perspective view of the dress skirt when opened and stretched at the waist in order to be put on, or taken off, by the wearer. Fig. II, is a similar perspective view of the skirt 15 as it would be when secured and in position on the wearer.

The skirt proper consists preferably of an upper portion 1, and lower portion 2, the former of which is preferably of non-elastic 20 material such as silk, and entirely plain or smooth on its surface, and the portion 2, may be fluted or ruffled, or both, as indicated in the drawings.

The upper portion is provided with a slit 25 or placket 3, at the back; fastening devices 4, of any convenient character, being applied at this region. In the instance shown these devices are ordinary spring ball and socket fasteners, such as are employed upon 30 gloves, etc. On each side of the skirt and in regions which do not extend in front of the hip portions a deep V-shaped gore 6, extends downward from the waist line. These 35 gores are filled by inserted pieces of material more elastic and preferably more pliable than that of the skirt proper, such as fine stockinette.

Strips 7, 7, of highly elastic material, such 40 as rubber webbing shown in the dotted lines, are inserted within casings at the rear half of the waist, the respective ends of each band being attached at substantially the front edge of each of the gores 6, and at a point 45 near the opening of the placket, and the intermediate portions of the band being free. The length of the rubber strips is such that when in their normal or unstretched position they conform substantially to the desired 50 waist measure of the garment; but they are capable of extension within their respective casings, so as to stretch the garment at the

waist line for convenience in putting it on and taking it off. It will be noted that the rubber strips are not restricted to the region of the gores, but extend rearwardly well beyond the same, and are free from attachment in the casings, except at the extreme rear end. 55

In Fig. I, the position of the parts is shown as the same appears when the rubber strips are stretched to their limit, the fullness of the rear portion of the garment at the waist region, corresponding with the length of the rubber strips when thus extended.

In Fig. II, where the rubber strips 7, 7, are represented as in their normal condition, or 60 unextended, it will be noted that while the garment is necessarily, gathered, this gathering is restricted to the extreme rear portion, and, furthermore, that at the sides where the gores occur the two edges of each gore are 65 permitted to approach very closely together by reason of the pliable and elastic character of the inserted pieces, so that an almost continuous and smooth surface of the silk, or other relatively-non-elastic material of which the 70 upper portion 1, is composed, may be presented.

The advantages of a garment of this character will be obvious wherever it is desired to have a very smooth and apparently tight-fitting surface at the front and sides of the 75 waist and hip portions, the wrinkling or gathering at the back being relatively inconspicuous as compared with the condition at the important regions at the front and sides. 80

I am aware that heretofore skirts have been made, of which the upper portion was wholly composed of elastic fabric, such a garment being patented in U. S. Letters Patent No. 662,714, dated November 27th, 1900, 85 granted to Henry J. Feuchtwanger. One of the purposes of the present invention is to permit the use of relatively non-elastic material for the upper portion of a skirt, while still obtaining the advantages of smooth 90 close fit characteristic of such patented skirts. Thus, in my improved garment, silk may be used for such upper portion; and yet the advantages of an elastic fabric at the important region may be obtained. 95

I am also aware that it is not broadly new to insert elastic gores at the waist region in 100

garments, or to employ elastic strips in such waist regions. I therefore do not claim the use of such devices individually.

Having thus described my invention, I claim:

In a garment having an upper portion of relatively non-elastic material, a pair of inserted gore pieces of relatively elastic and pliable material, arranged at each side of the waist line, and in the rear half of the circumference thereof; and strips of more elastic

material extending freely across the regions of said gores, and beyond the same to points at the extreme rear of the waist line, substantially as set forth.

In testimony whereof, I have hereunto signed my name, at Philadelphia, Pennsylvania, this 22nd day of January 1907.

JACOB GREENWALD.
